MULTISTAGE ROTARY COMPRESSOR

Karl Baumann, Wilmslow, England, assignor to
General Electric Company, a corporation of
New York

Application February 12, 1935, Serial No. 6,183
In Great Britain February 19, 1934

1 Claim. (Cl. 230—130)

This invention relates to multi-stage fluid compressors and pumps.

The object of the invention is to improve the efficiency of such machines and to simplify and 5 cheapen their construction.

According to the present invention a multi-stage fluid compressor or pump comprises two rotors mounted on parallel shafts and is formed with laterally extending plates partitioning the 10 machine into a series of parallel chambers each rotor comprising a plurality of sets of blades and the sets of rotor blades on the one shaft being located in chambers alternating with those in which the sets of blades on the other shaft are 15 located, said chambers being shaped to constitute discharge passages for the respective rotor blades and being provided with axially directed outlets for passing the fluid to the set of blades of the other rotor through which the fluid 20 next passes.

The rotation of the impeller shafts is preferably in the same direction such as could be obtained by a motor driving the two impellers through a gear wheel and two pinions.

25 The design is such that the discharge from the impeller mounted on one shaft is taken to the eye of the impeller mounted on a second shaft and so on.

In order that the invention may be more clearly understood reference will now be made to the 30 accompanying drawings which illustrate one suitable embodiment of the invention and wherein—

Fig. 1 is a plan view of a machine embodying the invention, part of the machine being shown 35 as a horizontal section through the shaft centres.

Fig. 2 is a section to a reduced scale on the line II—II of Fig. 1.

Fig. 3 is a section on the line III—III of Fig. 1.

Fig. 4 is a section corresponding to Fig. 2 but 40 showing the modifications necessary for passing the fluid through a cooler.

In the drawings a number of parts on the left side of the machine correspond to parts on the right side, and where this occurs the reference numerals to the parts on the left side have been designated by the suffix *a* whilst the corresponding part on the right side has been designated by the suffix *b*.

Referring to the drawings 1 represents the casing of the machine and 2*a* and 2*b* are the rotor shafts on which are mounted sets of rotor blades 3*a* and 3*b* respectively. The space within the casing is divided by lateral plates 4 into a series of chambers 5.

55 Each alternate chamber 5 referred to herein

by the reference 5*a* contains a set of the blades 3*a* whilst each of the intervening chambers designated by the reference 5*b* contains a set of the blades 3*b*. It is intended that in the arrangement shown each of the rotors will rotate in a counter clockwise direction. 5

The chambers 5*a* and 5*b* are each shaped to constitute a fixed discharge passage for conducting the fluid discharged from the respective rotor blades located in the chamber in question 10 to the set of rotor blades in an adjacent chamber through which the fluid next passes.

Each of the chambers 5*a* accordingly comprises a portion 6*a* (see Fig. 2) surrounding the set of blades 3*a* in question, a cross-over passage 7 and 15 a portion 8*b* surrounding the shaft 2*b* and located between adjacent sets of rotor blades 3*b*. In each of the chamber portions 8*b* there is formed an annular convergent portion 9*b* terminating in a lateral outlet 10*b*. The fluid passes 20 from each outlet 10*b* to the eye 11*b* of the rotor blades 3*b* located in the next adjacent chamber.

Similarly as shown more clearly in Fig. 3 each of the chambers 5*b* comprises a portion 6*b* surrounding the blades 3*b* a cross-over passage 12 25 and a portion 8*a* located around the shaft 2*a* terminating in a convergent passage 9*a* and lateral outlet 10*a*.

It will be observed that in the arrangement shown the cross-over passages 7 are located on 30 the under side of the machine whereas the passages 12 are located in the upper part of the machine.

Around each set of rotor blades 3*a* and 3*b* are diverging portions 13*a* and 13*b* respectively into which the fluid from the rotors is discharged whilst each of the passageways 9*a* and 9*b* preferably contain fins 14*a* and 14*b* respectively for the purpose of preventing vortices. 35

This fluid leaving a set of rotor blades 3*a* will 40 pass through the chamber portion 6*a*, cross-over passage 7 into the associated chamber portion 8*b* on the other side of the machine; thence it will pass through discharge passage 9*b* and outlet 10*b* into the eye of the rotor blades 3*b* in 45 the next chamber. From the rotor blades 3*b* the fluid will similarly pass into chamber portions 6*b* and thence through cross-over passage 12 to chamber portion 8*a* on the left side of the machine. From the chamber portion 8*a* the 50 fluid will pass through passageway 9*a* and outlet 10*a* to the rotor blades 3*a* in the next chamber and so on passing alternately through a set of blades 3*a* and then a set of blades 3*b*. Referring to Fig. 4 the fluid will progress from ton 55

to bottom of the figure through each chamber in turn.

It will be appreciated that with such an arrangement the change of direction of the fluid 5 is considerably reduced in comparison with usual arrangements since the path through an impeller and the discharge path from it are kept in the same plane, thus friction losses are appreciably reduced.

10 In order to keep friction losses low the peripheries of the passage portions 6a and 6b are preferably of an involute shape as clearly shown in the drawings.

15 The plates 6 may conveniently be of steel thus enabling smoother passages to be obtained and reducing the cost of construction as compared with cast iron due to the elimination of machining and chipping.

Furthermore, the construction may be so arranged that the joints in the various static parts such as those between the plates 6 and the casing 5 may be made by welding or alternatively the structure may be supported by riveting or like methods of assembly.

20 The construction also lends itself readily to cooling between stages and Fig. 4 is a section corresponding to Fig. 2 of a chamber 5a which is modified to allow of the fluid being passed through a cooler during its passage between the 25 rotor blades 3a and the outlet 11b. The chamber portion 6a is formed with a discharge passage 15, provided with baffles 16 leading to the

cooler (not shown), whilst the chamber portion 8b is formed with a passageway 17 similarly provided with baffles 18 which conducts the fluid from the cooler to the chamber 8b.

It will be appreciated that cooling will in general only be effected between some of the stages, for instance after leaving every third or fourth impeller blade depending upon the design of the apparatus. 5

I claim:

A multi-stage rotary compressor including the combination of a fabricated casing having an outer wall, two rotors with parallel shafts and a plurality of impellers disposed in the casing, a plurality of substantially parallel plates 15 extending laterally within the casing and welded to the outer wall to define a plurality of chambers, each chamber containing one impeller and a curved partition disposed centrally between the shafts to define together with said outer wall 20 a channel for conducting fluid discharged from a first impeller disposed in one chamber to a second impeller disposed in another chamber, said channel having an involute portion adjacent the first and the second impeller and a substantially straight cross-over portion connecting the involute portions, and aligned inlet and outlet conduits secured to opposite ends of an upper portion of the outer casing intermediate the horizontal projection of the parallel shafts. 25 30

KARL BAUMANN.
